Patented February 7, 1905.

UNITED STATES PATENT OFFICE.

JOHN DAEHLER, OF LOS ANGELES, CALIFORNIA.

DESIGN FOR A TOILET-POWDER BOX.

SPECIFICATION forming part of Design No. 37,320, dated February 7, 1905.

Application filed August 5, 1904. Serial No. 219,671. Term of patent 3½ years.

To all whom it may concern:

Be it known that I, JOHN DAEHLER, a citizen of the United States, residing at Los Angeles, in the county of Los Angeles and State 5 of California, have invented a new, original, and ornamental Design for a Toilet-Powder Box, of which the following is a specification, reference being had to the accompanying drawing, forming part thereof.

10 The accompanying drawing is a view in perspective, showing the design of a toilet-powder box.

What I claim as new, and desire to secure by Letters Patent, is—

The ornamental design for a toilet-powder 15 box.

JOHN DAEHLER.
